Attorneys.

UNITED STATES PATENT OFFICE.

STERLING D. ROSAN, OF BOSTON, MASSACHUSETTS.

GOLF-CLUB GRIP.

Application filed February 18, 1928. Serial No. 255,258.

The object of this invention is to cure certain faults prevalent among golf players as, for example, such common tendencies as (1) to draw in the hands in striking the ball instead of following through, thereby slicing to the right, (2) to cramp the hands and arms on the back swing instead of maintaining free wrist action, (3) to become tense in fingers and thence throughout the arms and legs, (4) to cause the hands to swing through in advance of the club head as the ball is struck, (5) to lose balance in the swing, and (6) to fail to time the swing properly. More particularly the objects of the invention are to correct the tendency of the right hand to assume too much control of the club and to confine the grip of the club by the right hand largely to those fingers more remote from the thumb.

According to this invention the end of the forefinger of the right hand (and preferably of each of the first two fingers) is held away from the club shaft so that the finger can not grip the shaft, whereby the right hand is restrained from assuming more than its proper share of the control of the club and the grip of the club is largely confined to a shorter length of the club, namely, the fingers of the left hand and only a portion of the fingers of the right hand instead of all the fingers of both hands. The aforesaid forefinger is held away from the club by means projecting from the club, preferably the surface of a member which is detachable from the club rather than integral therewith. To counteract the torque applied to the club by the forefinger bearing on this surface, tending to rotate the club about its axis, an oppositely directed surface is preferably provided for the thumb of the right hand, the latter surface also preferably being disposed on the detachable part. In the preferred embodiment these surfaces are located on opposite sides of a flexible clip adapted to grip the club, the central portion of the clip engaging the club and the free ends of the clip engaging the finger and thumb, this arrangement being more convenient and effective than the reverse arrangement in which the ends of the clip grip the club and the central portion projects upwardly from the shaft between the finger and thumb.

For the purpose of illustration I have shown one concrete embodiment of the invention in the accompanying drawings, in which:

Fig. 1 is a perspective view of the preferred embodiment of the invention gripped around the shaft of a golf club by the right hand;

Fig. 2 is a perspective view of the same embodiment; and

Fig. 3 is a cross section of the embodiment applied to a golf club.

The particular embodiment of the invention chosen for the purpose of illustration is preferably formed of flexible celluloid in the shape shown in the drawings, that is, having a U-shape central portion 1 adapted to fit around the golf club shaft and two flanges projecting tangentially from the club, the flange 2 engaging the thumb and the flange 3 engaging the forefinger at the lip 4 and also preferably engaging the second finger at the lip 5. As shown in Fig. 1 the flange 2 preferably extends substantially the whole length of the thumb and, as shown in Fig. 3, this flange is preferably curved outwardly to fit the contour of the thumb. While the lips 4 and 5 may be formed as a continuous single lip, the portion between the two fingers is not essential and therefore is preferably omitted as indicated by the depression 6 in Fig. 2. The finger flange 3 may also have an outwardly turned lip 7 at the rear end to fit the contour of the second finger and to lie between the ends of the second and third fingers, thereby serving more readily to position the grip in the hand. The normal diameter of the semicircular portion 1 may be somewhat more or less than or equal to the diameter of the shaft but it is preferably somewhat less than the diameter so that the flexible clip will snap over the shaft and remain in position by virtue of its own elasticity if the hand is temporarily removed from the club. However the resiliency of the clip, especially if made of celluloid, will ordinarily be so slight that the clip may readily be removed from the club by merely pulling downwardly with the thumb and fingers engaging the clip as illustrated in Fig. 1. While the surfaces of the flanges 2 and 3 against which the thumb and fingers engage may be formed as an integral part of the club, as for example by permanently attaching the grip to the club, the clip is preferably unattached to the club so that it may be used interchangeably upon any club of a set. It will be understood of course that while the clip is preferably flexible it offers sufficient resistance to flexure to hold the ends of the fingers

away from the club when gripped with any reasonable degree of pressure.

In use the club is gripped with the device in the position shown in Fig. 1 so that the 5 first two fingers on the right hand are held, at their outer ends, away from the shaft, whereby the right hand is restrained from taking too much control from the left hand and the effective grip of the club is shortened 10 to afford more flexibility and less constraint in the swing, both backwardly and forwardly. While the device may be used indefinitely it is intended to be used only until the 15 left hand and arm are trained to assume their proper share in the swing and control of the club.

I claim:

1. A golf club grip comprising means projecting from the shaft of the club to provide 20 a surface for the thumb of the right hand and an oppositely directed surface for holding the forefinger of the right hand away from the shaft, that portion of the finger surface engaged by the end of the forefinger being 25 spaced farther away from the axis of the shaft than the surface engaged by the middle of the forefinger.

2. A golf club grip comprising a clip 30 curved to fit the club shaft and having oppositely directed surfaces for the thumb and forefinger respectively of the right hand so that pressure on said surfaces clamps the grip to the shaft, the surface for the forefinger ex-

tending tangentially from the shaft to hold the end of the finger away from the shaft. 35

3. A golf club grip comprising a flexible clip having its central portion curved to fit the club shaft and having end portions presenting oppositely directed surfaces for the thumb and forefinger respectively of the 40 right hand so that pressure on said end portions tends to clamp the central portion around the shaft, one of said end portions extending tangentially from the shaft to hold the end of said finger away from the shaft. 45

4. A golf club grip comprising means projecting from the shaft of the club to provide a surface for the thumb of the right hand and an oppositely directed surface for holding the end of the forefinger of the right 50 hand farther away from the shaft than the base of said finger, that portion of the finger surface engaged by the end of the forefinger being spaced farther away from the axis of the shaft than the surface engaged by the 55 middle of the forefinger.

5. A golf club grip comprising a flexible clip shaped to straddle the shaft of a golf club and to engage the shaft loosely so as to be readily removable therefrom, the clip 60 having a flange projecting tangentially from the shaft, whereby a part of the hand is held away from the shaft.

Signed by me at Boston, Massachusetts,
this sixteenth day of February, 1928.

STERLING D. ROSAN.
